BY Frank S. Seiderheim, ATTORNEY.

UNITED STATES PATENT OFFICE.

CHARLES FEARON, OF PHILADELPHIA, PENNSYLVANIA.

GAME-COUNTER.

SPECIFICATION forming part of Letters Patent No. 380,428, dated April 3, 1888.

Application filed December 13, 1886. Serial No. 221,417. (No model.)

To all whom it may concern:

Be it known that I, CHARLES FEARON, a citizen of the United States, residing in the city and county of Philadelphia, State of Pennsylvania, have invented a new and useful Improvement in Game-Counters, which improvement is fully set forth in the following specification and accompanying drawings, in which—

Figure 1 represents a top or plan view of a game-counter embodying my invention. Fig. 2 represents a transverse section thereof in line $\alpha\alpha$, Fig. 1.

Similar letters of reference indicate corresponding parts in the two figures.

My invention consists of a game-counter formed of a body having pivoted thereto indicators designating the different suits of a pack of playing-cards.

It also consists of the body of the counter provided with indices for the number of games and points of a game, the construction of the body and indices being hereinafter fully set forth.

Referring to the drawings, A represents the body of a game-counter formed of any suitable material and having marked on its face two series of numbers, as at B and C, for the number of games and the points thereof. The body has in its upper face a longitudinally-extending recess, D, and above the same the slots E, which extend parallel with said recess, leaving the bars F G G for the support of the sliding indices H, the latter being bent so as to have their heel ends beneath the bars G in the recess D, whereby the indices are connected with the plate, and as they are freely fitted in the slots E they may be moved to either of the numbers B C, respectively, for counting the

number of games and the number of points made.

To the side of the body A is pivoted a number of plates, J, which are of the form of the trumps of a pack of cards—in the present case a spade, heart, club, and diamond; but, if desired, the form of said trumps may be printed, painted, or otherwise marked on said plates.

It will be seen that the plates may be moved from vertical to horizontal planes, and vice versa. Consequently, when a trump is made or announced the plate corresponding to the same is thrown up (or down, if preferred,) thus showing plainly to the players the nature of said trump.

Each index H is shown as made of two pieces of material; but, as is evident, it may be made of a single piece properly shaped and bent.

Having thus described my invention, what I claim as new, and desire to secure by Letters Patent, is—

1. A game-counter having movable indices to indicate the number of games and points, and plates of the form of the different suits of a pack of playing-cards, hinged to the side of the counter to indicate the trump-suit, all as described.

2. A game-counter consisting of the body A, with a recess, slots, and bars, bent indices movably fitted to said bars, and trump-indicating plates pivoted or hinged to said body, substantially as described.

CHAS. FEARON.
